CLOTHESLINE TENSIONING AND POSITIONING DEVICE

Daniel E. Belich, West Allis, Wis.

Application April 29, 1946, Serial No. 665,810

7 Claims. (Cl. 248—353)

1

My invention relates to improvements in clothes line tensioning and positioning devices for use between fixed points of support.

My primary object is to provide a clothes line tensioning device which can easily be operated by inexperienced and weak persons without danger of personal injury, and which can be used either in combination with a so-called clothes line prop or independently.

A further object is to provide a combination tensioning device and clothes line prop in which the tensioning means will be largely concealed within a cylindrical or tubular prop of neat and attractive appearance and light weight.

Still further objects are to provide an inexpensive combination tensioning device and prop; to provide such devices with either hand operated or foot operated tensioning and locking means; to provide means whereby a clothes line may be elevated above the normal height of the prop and above the fixed end connections of the line by operation of the tensioning means, whereby sufficient downward pressure may be applied to the prop to prevent it from swaying materially; to provide resilient means for projecting a line engaging hook above the prop preparatory to a line tensioning operation; and, in general, to provide improved means operative between fixed supports to which a clothes line is attached for handily and quickly positioning the line at a desired elevation under a proper tension for supporting wet clothing in windy weather.

In the drawings:

Figure 1 is an elevational sectional view of a combined clothes line prop and tensioning device embodying my invention, with dotted lines illustrating the tensioning means in extended position.

Figure 2 is a sectional view of the upper end portion of the device shown in Figure 1, taken at right angles to that of Figure 1.

Figure 3 is a view similar to Figure 1, showing a modified form of construction.

Figure 4 is a sectional view of a device embodying my invention when adapted for use independently of a clothes line prop.

Figure 5 is a sectional view of the same taken at right angles to Figure 4.

Like parts are identified by the same reference characters throughout the several views.

In Figure 1 the lower portion or prop member 10 of the prop is preferably of circular cross section and has a metal base piece 11. The prop portion 10 may comprise metal tubing, bamboo,

2

or any other suitable material of the desired strength and minimum weight. At least its upper end portion is hollow or tubular in form and provided with an aperture 12 and, above the aperture, with one or more slots 14. In the construction shown there are two of these slots, and they are diametrically opposite, for reasons hereinafter explained.

The portion of prop 10, about the aperture 12, is encased by a jacket or housing 15, preferably of metal, and having a portion 16 which houses a ratchet wheel 17 and a winding drum or spool 18. The ratchet wheel and spool are mounted on a shaft 19 journaled in the walls 15 of the housing and which has an exterior crank 20. A pawl 21 extends through an aperture in the housing to which it is pivoted at 16. This pawl has an exterior operating handle 22.

The upper portion of the prop member 10 is provided with a sliding sleeve-like jacket 30 which normally covers the slots 14 and is provided above the member 10 with upwardly and laterally extending parallel walls 32. The upper margins of the walls 32 preferably each have an arcuate central depression or notch 33 on each side of which the walls are connected by shafts 34 which carry pulleys 35. When these pulleys are applied to a clothes line A, as indicated by full lines in Figure 1, the line may be tensioned by the means now to be described.

Between pulleys 35 there is a line engaging hook 36, the shank of which is secured to a cap 37 which has the form of an inverted cup encasing the upper end of member 10. Within this cap, and secured to its top wall, there is a U-shaped bracket 38 which carries a pulley 39.

The sliding sleeve 30 has a cross pin 42 near its lower end which extends through the slots 14, and this cross pin is connected with the winding drum or spool 18 by a flexible connection such as the cord 43, which extends upwardly over the pulley 39 and thence downwardly about a roller 44 on another cross pin 45, and thence to the winding spool 18, to which it is secured for winding purposes.

Operation of the crank 12 in one direction will wind the cord 43 upon the spool 18, thus causing the other end of the cord to lift the cross pin 42 and sliding jacket 30, thus raising the pulleys 35 above the hook 36 to or toward the dotted line position.

In operation, the hook 36 will first be engaged with a clothes line A to be tensioned and the prop will be manipulated to cause the clothes line

to extend over the pulleys 35, as indicated by full lines in Figure 1. The line may then be tensioned by rotating the crank 12 to wind the cord 43 on the spool 18, thus causing the cord to draw the sleeve 30 and its pulleys 35 upwardly to or toward the dotted line position. In the meantime, the prop will be in a vertical position, with its lower end resting upon the ground, and as the line is tensioned, the portion engaged by the pulleys will be lifted from its sagging position to a position above the fixed ends of the line, whereby the line tension will not only prevent the line from sagging but will press the prop downwardly into forcible contact with the ground below the line. If sufficient tension is applied, the prop will thus be held in a substantially vertical position and material swaying thereof prevented when the clothing on the line is being blown by the wind. Since tensioning is accomplished by raising the pulleys 35 above the hook 36, the portion A' of the clothes line will be drawn into the tubular sleeve 30, and the amount of slack taken up will be twice the distance between the hook and the pulleys.

When the desired tension has been applied, the pawl 21 will lock the ratchet wheel 17 and its associated spool 18 until the pawl is released by pressure upon its handle 22, whereupon the tension on the line will be relieved and the jacket 39 restored to its normal position covering the slots 14 in the member 10.

If desired, the cross pin 42 may be connected by a tension spring 50 with another cross pin 51 to ensure a prompt return of the sleeve 30 to its normal position. However, gravity may be ordinarily relied upon for this purpose.

In the embodiment of my invention shown in Figure 3, the pulleys 135 are mounted between parallel walls 132 which project upwardly from a collar-like fitting 130 applied to the upper end of a tubular prop 110. The hook 136 has an elongated shank or rod 55 which extends downwardly through the fixed guides 56 and 57, with its lower end connected to a slide 58 from which a pedal 59 extends through a slot 60 in the prop 110. A coiled tension spring 62 connects the fixed guide 57 with the slide 58 and tends to hold the latter in a raised position with the hook 136 above the pulleys 135. But downward pressure applied by the foot of the operator to the pedal 59 will depress the pedal and draw the hook 136 into the tubular prop with a portion A' of an engaged clothes line, thus tensioning the line.

In tensioning position, the rod 55 may be automatically locked by a spring actuated dog 65 pivoted at 66 to the pedal 59. The spring 67 urges the inner end of the dog into cam-like engagement with the prop at 68. But the outer end portion 70 of the dog extends beyond the pedal 59 whereby foot pressure applied to this end of the dog will lift its inner end out of locking position and allow spring 62 to lift the hook 136 above the pulleys 135, thus relieving the tension.

When the hook 136 is in tensioning position it may, if desired, be additionally secured by a set screw 72, threaded in the prop and the guide member 57 with its inner end in clamping engagement with the rod 55. This locking means may be utilized to prevent children, tampering with the pivoted locking dog 65, from releasing the line tension.

In Figures 4 and 5, another modification of my invention is illustrated, in which a short piece of tubing 210 is substituted for the prop shown

in the other views. A collar-like fitting 230 at the upper end of the tube 210 has upwardly extending walls 232 which carry line engaging pulleys 235 between which the hook shank 255 normally extends. The hook shank 255 has a hook 236 at its upper end and its lower end is connected with a sliding guide 258. The lower end of the tube 210 is capped at 211 and a tensioning rod 80 is rotatably mounted in the cap 211 with its lower end provided with a hand actuated crank 81 and its upper end in threaded engagement with the guide 258, as best shown in Figure 5. The hook 236 is engaged with a clothes line and drawn between the pulleys by the tensioning rod 80 in the same manner as in Figure 3, but more slowly, and the entire assembly is left suspended on the clothes line, preferably in the vicinity of a fixed support 82 to which one end of the line is secured.

Attempts heretofore made to tension a clothes line by folding a portion of it upon itself between two proximal points of support have not been commercially successful because of excessive weight, exposure to the tensioning means, and danger of injury to the operator, and also because the tension could be readily relieved by children playing in the vicinity.

My improved tensioning means is largely concealed, easily manipulated, and whether used independently or in connection with a prop it can be made of such light weight, at small expense, and with public approval.

I claim:

1. A clothes line tensioning device, comprising the combination with a portable prop member having a hollow upper end portion longitudinally slotted and provided with a sleeve-like jacket, a cross pin extending through said slots at the lower end of said jacket, a set of spaced line supports carried by the upper end of the jacket, a line engaging hook normally supported by said prop member in an exposed position substantially in line with the extended axis of the prop member, and manually operable means for lifting the jacket to adjust said line supports above the hook, whereby the hook engaged portion of the line may be drawn into the jacket.

2. A clothes line tensioning device comprising the combination of a portable clothes line prop member having a longitudinally slotted hollow upper end portion of circular cross section, a cap for the upper end of the prop member provided with an interior pulley and an exterior hook, a jacket mounted to slide on the upper end of the prop member and provided with a cross pin extending through the slots in the prop member, a set of clothes line engaging pulleys mounted on the upper end of the jacket, a winding spool on the prop member below the jacket, and a jacket lifting cord having its ends connected with the winding spool and cross pins, respectively, with an intermediate portion extending over said interior pulley, and means for manually rotating said spool to lift the jacket to extend the length of the prop and adjust its line engaging pulleys above the hook and draw the hook engaged portion of the line into the jacket.

3. A clothes line tensioning device comprising a tubular prop, a line engaging hook mounted on the prop, a plurality of pulleys mounted on the prop in spaced relation for passage of the hook therebetween, and means for causing relative movement between the hook and pulleys for drawing line slack into concealed position into and holding the slack within the prop.

4. A clothes line tensioning device comprising

a tubular prop having telescopic sections, a line engaging hook mounted on the prop, a plurality of pulleys mounted on one prop section and in spaced relation for passage of the hook therebetween, and means for moving said one prop section relative to the hook for drawing line slack into concealed position into and holding the slack within the prop.

5. A clothes line prop and tightener comprising first and second relatively extensible elements having bearing portions upon which the first element is upwardly extensible and downwardly retractable respecting the second, said second element having a ground engaging foot, three line guiding members fully exposed in the retracted relative position of said first element to receive an unbroken line, two of said members comprising pulleys mounted in laterally spaced positions on said first element and the other member being mounted on the second element between the pulleys in a position to hook over the unbroken line passing between the pulleys and to form a bight in such line as said first element is extended, whereby said line may be tightened as an incident to its support by said prop, and means for fixing said first element in extended position on the second.

6. A clothes line prop and tightener comprising first and second relatively extensible elements having bearing portions upon which the first element is upwardly extensible and downwardly retractable respecting the second, said second element having a ground engaging foot, three line guiding members fully exposed in the retracted relative position of said first element to receive an unbroken line, two of said members comprising pulleys mounted in laterally spaced positions on said first element and the other member being mounted on the second element between the pulleys in a position to hook over

25

40

the unbroken line passing between the pulleys and to form a bight in such line as said first element is extended, whereby said line may be tightened as an incident to its support by said prop, and means for fixing said first element in extended position on the second in further combination with means comprising a crank and a drum, on one of said elements and a line connected with the drum and with the other element for extending said first element to tighten and prop the clothes line.

10. The device of claim 6 in which the drum is mounted on the second element and the second element has pulley means above the lower end of the first element and over which the line connected with the drum and with the first element passes to exert upward pull on the first element, the respective elements being tubular and the last line and said pulley means being housed within the second element and having a connection laterally through the second element to the first element.
